CLAIM

(52) **U.S. Cl.** **D8/373**

The ornamental design for an actuatable holding system, as shown and described.

(58) **Field of Classification Search** D8/354,
D8/373; D6/552, 547; 248/231.51, 316,
248/5; 24/598.5; 211/70.6

DESCRIPTION

See application file for complete search history.

(56) **References Cited**

FIG. 1 is a lower-front perspective view of the ornamental design for an entire configuration for an actuatable holding system according to the invention, with the arms shown in a closed position.

U.S. PATENT DOCUMENTS

FIG. 2 is a lower-front perspective view of the ornamental design for an entire configuration for an actuatable holding system according to the invention, with the arms shown in an opened position.
